UNITED STATES PATENT OFFICE.

BOLESLAW DUTKIEWICZ, OF LODZ, RUSSIA.

THREAD STOP-MOTION FOR GRIPPING A BROKEN THREAD IN TWISTING-MACHINES.

1,082,016.

Specification of Letters Patent.

Patented Dec. 23, 1913.

Application filed June 6, 1913. Serial No. 772,168.

To all whom it may concern:

Be it known that I, BOLESLAW DUTKIEWICZ, a subject of the Emperor of Russia, residing at Lodz, Russia, have invented 5 certain new and useful Improvements in Thread Stop-Motions for Gripping a Broken Thread in Twisting-Machines, of which the following is a specification.

This invention relates to a thread stop motion for gripping a broken thread for the purpose of preventing the thread from being wound on the cylinder and thus avoiding the consequent loss of time and yarn.

The object of the invention is to provide 15 for a construction preventing all access of dust to the gripping place so that the broken thread is surely gripped up.

Besides this invention provides for means 20 for regulating the thread tension consisting in a weight slidably mounted on the lever of the thread stop motion and producing a more or less intensive tension of the thread corresponding to the distance of the axis of lever. These regulating means are 25 necessary because of the different strength of threads which are to be handled in twisting machines.

Finally the invention provides for means 30 for facilitating the introduction of the thread into the thread stop motion.

The invention will be now described by aid of the accompanying sheet of illustrative drawings.

In the drawings: Figure 1 is a side view 35 of the thread stop motion applied to a twisting machine. Figs. 2 and 3 are side views drawn to a larger scale showing the thread stop motion respectively when gripping the thread and when in its normal position. Fig. 4 is a front view of the main portion of the thread stop motion; and Fig. 5 is a plan of the thread stop motion.

As shown the twisting machine itself retains substantially its ordinary construction. The thread 1 is drawn from the thread spool 2 which is mounted on pins 3 45 on the framing of the machine. The thread 1 passes first around the lower roller 4, then around the upper roller 5, and goes finally 50 to the thread bobbin 6.

The thread stop motion is mounted on a longitudinal bar 7 by means of a plate 8 which may be of U-shape and is fixed on the bar 7 by means of a screw or screws 9. 55 The upper end of this plate 8 carries a sleeve 10 inclosing the pivot pin 11 of the

thread stop motion. This pin 11 and the sleeve 10 are each provided with slots 12 (Fig. 3) whereby two tongues are formed on the sleeve and pin, namely a lower 60 tongue 13 and an upper tongue 14. The ends of the slots are formed with preferably round and slightly enlarged openings 16.

In the working of the machine the thread passes through the enlarged rounded inner 65 end 16 of the slot 12. The sleeve 10 is formed with a transverse slot 17 (Fig. 5) through which a screw 18 passes and enters the pin 11. The arrangement is designed to limit the extent to which the pin 11 can 70 turn in the sleeve 10.

The non-slotted end of the pin 11 carries a lever 19 on one end of which is a sliding weight 20. The lever 19 is preferably formed with a number of holes 21 in which 75 a screw 22 can be inserted for fixing the weight 20 at different distances from the pin 11, the weight being shifted nearer the said pin when dealing with fine thread, whereas it is moved farther away from the 80 pin for coarse thread. The other end of the lever 19 is constructed as a thread guide 23 having a hooked end 24 for guiding the thread.

For the purpose of guiding the thread 85 through the slot 12, a thread guide 25 is provided on one side of the plate 8 and a thread protector 26 is arranged on the other side.

The operation of the improved apparatus 90 is as follows: In the normal working of the twisting machine the thread stop motion is maintained in the position shown in Figs. 1 and 3 by the tension of the thread. In this position the slots in the sleeve 10 and 95 the pin 11 coincide with each other so that the thread is able to pass freely therethrough the parts 25 and 26 maintaining the thread in such a position that it passes through the slot without friction, so that 100 only the readily replaceable parts 25 and 26 are subjected to wear. If the thread should happen to break the weight 20 comes into operation and the thread assumes the position shown in Fig. 2. By this means the 105 thread is gripped very effectively and reliably between the pivot pin 11 and the sleeve 10 because it is gripped at two places, namely on both of the slots 12, and it is also made to assume a zig-zag form. It is 110 reliable because the gripping surfaces of the sleeve and the pivot pin are not exposed

to contact with dust in any way, since they are completely shut in, so that they must necessarily remain always quite clean, and as will be clearly understood, a deposit of 5 dust on the two surfaces of the slot 12 that surround the thread has no influence whatever on the action and reliability of the thread stop motion. At the same time as will also be perceived from Fig. 2, the 10 broken off portion 1¹ of the thread is lifted by the swung-up thread guide 23 out of the range of the thread bobbin and rollers 4 and 5, thus preventing also any interference with the machinery or working parts from 15 this cause. The thread guide in swinging up with the broken off portion of the thread hanging from it also draws the attention of the attendant who can then immediately remedy the fault.

20 As already stated hereinbefore the insertion of the thread is facilitated according to this invention by making the part 14 shorter than the part 13. By this shortening a kind of saddle 15 is produced that serves as a 25 guide for the thread which is to be inserted and which can be inserted without trouble into the slot 12 and the openings 16.

Having now described my invention, what I claim is:

30 1. A thread stop motion comprising a sleeve provided with a longitudinal slot, a

pin pivotally mounted in the said sleeve and likewise provided with a longitudinal slot, the two slots normally registering with each other and allowing the passage of the 35 thread, a double armed lever fixedly connected with the non-slotted end of the said pin and a weight slidably mounted on the one arm of the said lever the other arm terminating in a hook supporting the 40 thread.

2. A thread stop motion comprising a sleeve provided with a longitudinal slot, a pin pivotally mounted in the said sleeve and likewise provided with a longitudinal slot, 45 the two slots normally registering with each other and allowing the passage of the thread, a double armed lever fixedly connected with the non-slotted end of the said pin and a weight slidably mounted on the 50 one arm of the said lever the other arm terminating in a hook supporting the thread, the said pin and sleeve being shortened above the slot so that the projecting lower portion of the pin and sleeve serves 55 as a guide for inserting the thread.

In testimony whereof I affix my signature in presence of two witnesses.

BOLESLAW DUTKIEWICZ.
